ATTACHMENT FOR SEWING MACHINES

John D. Karle, Roselle Park, N. J., assignor to
The Singer Manufacturing Company, Eliza-
beth, N. J., a corporation of New Jersey

Application July 20, 1935, Serial No. 32,349

8 Claims. (Cl. 112—160)

This invention relates to sewing machines and more particularly to a presser-foot which is vibrated laterally of the line of seam and is adapted to be used for making ornamental seams.

5 The several features of the present invention will be clearly understood from the following description and accompanying drawings in which:—

10 Figure 1 is a front elevation of a zigzag-stitching attachment with my improved presser-foot attached, showing the needle in raised position and the position of the presser-foot at the completion of the right to left shifting movement.

15 Figure 2 is an elevation similar to Figure 1 showing the position of the presser-foot after the left to right shifting movement has been completed.

Figure 3 is a top plan view of the presser-foot.

20 Figure 4 is a bottom plan view of the presser-foot.

Figure 5 is a sectional view taken substantially along the line 5—5 of Figure 3.

25 Figure 6 is a side elevation of the stitch-finger, and Figure 7 is a top plan view of the finished work showing the seam produced by the attachment.

30 This invention is shown applied to a zigzag-stitching attachment comprising a plate 10 fixed to the presser-bar of the machine and formed with a cross-arm 11 which slidably carries a bar 12 having a depending portion 13. Pivotally secured by the pivot-pin 14 to the plate 10 is a lever 15 which is actuated by the needle-clamp 16 carried by the usual reciprocating needle-bar 17 journaled in the head of the machine and carrying a needle 17.

35 The lever 15 carries a spring-pressed pawl 18 which actuates a ratchet-wheel 19 pivoted on the plate 10 and having rigidly attached to its rear face a cam 20 the circumferentially spaced projections of which engage the inwardly extending projections 21 formed on the member 22 which is fulcrumed on the pivot-pin 23. Pivotally secured by the screw 24 to the upstanding post 25 of the cross-arm 11 is a bell-crank lever 26 one arm of which is bifurcated to receive the stud 27 carried by the swingable member 22 and the other arm formed with an arcuate slot 28. A link 29 operatively connects the slide-bar 12 to the bell-crank lever 26 and has one of its ends secured by the pivot-pin 30 to the bar 12 and its other end adjustably secured to the bell-crank lever by the thumb-screw 31 which extends 45 through the arcuate slot 28. The above described

mechanism for vibrating the presser-foot laterally of the line of seam formation is shown in my co-pending application Serial No. 758,381, filed on December 20, 1934, to which reference may be had for a more detailed disclosure.

5 My improved presser-foot comprises a shank 32 which is adapted to be removably secured to the depending portion 13 of the slide-bar 12 by the screw 33. The shank 32 carries a rectangular shaped sole-portion 34 which is formed with a needle-opening 35 and a work-engaging surface. The lower face of the sole-plate in rear of the needle-opening is cut away to provide a clearance groove 37 for the thread-loops and the sole-plate in front of the needle-opening 35 is 10 formed with a half-round groove 36 which leads to the needle-opening to provide clearance for the initial stitches of the raised ornamental seam when laid in circular form.

15 A stitch-supporting finger having its shank 39 20 in the same horizontal plane as the upper face of the sole-portion is adjustably secured thereto by the screw 40. The free end of the stitch-finger extends into the needle-opening and is formed with a downwardly inclined thread-deflecting portion 41 and a rearwardly extending widthwise tapered tongue 42 which is in substantially the same horizontal plane as the lower face of the sole-plate and extends through the groove 37.

30 Operation

35 On the upward movement of the needle-bar 17 the needle-clamp 16 engages the free end of the lever 15 and moves the lever 15 and pawl 18 upwardly. During its upward movement the pawl 18 engages the ratchet-wheel 19 and advances it and the cam 20 one-eighth of a revolution. The rotation of the cam 20 causes one of its circumferentially spaced projections to contact one of the inwardly extending projections 21 on the swinging member thereby causing the member to swing in a clockwise direction about its pivot 23. This swinging movement causes the pin 27 to swing the bell-crank lever 26 in a counter-clockwise direction about its pivot and this movement is imparted to the slide-bar 12 by means of the link 29 thereby causing the presser-foot to move to the left to the position shown in Figure 1. The shifting of the presser-foot occurs 45 while the usual feed-dog 44 is below the throat-plate 45 and is completed just prior to the point in the cycle when the feed-dog contacts the work. After the feed-dog has advanced the work, the needle descends forming the stitch on the right 50

side of the stitch-finger, (Fig. 1), and on the up-stroke of the needle the needle-clamp 16 again engages the free end of the lever 15 and the pawl again advances the ratchet-wheel and cam 20.

- 5 The movement of the cam causes the swingable member 22 to shift in a counter-clockwise direction about its pivot and this movement is transmitted to the bar 12 by the bell-crank-lever 26 and the link 29, thereby shifting the presser-foot 10 to the right to the position shown in Figure 2. The needle then descends on the left side of the stitch-finger forming a stitch and the needle-thread extends from the first needle-hole across the stitch-finger to the second needle-hole. From 15 the foregoing it will be observed that the zigzag attachment acts to shift the presser-foot laterally of the line of seam formation so that the needle descends first on one side of the stitch-finger and then on the other. The tension on the thread is 20 comparatively tight and as the stitches are formed over the stitch-finger the stitches which have been laid over the finger cause the work to move with the presser-foot whereby the work is shifted laterally relative to the needle. The 25 stitches 46 are formed near the top of the downwardly inclined thread-deflecting portion 41 of the stitch-finger and when the stitch is being set the tension on the needle-thread causes the thread overlying the stitch-finger to slide down 30 the downwardly inclined portion of the stitch-finger so that the thread will be moved in rear of the needle-path to prevent its being pierced by the needle during the succeeding stitch-forming cycle.
- 35 Upon continued operation of the machine a series of stitches 46, (Fig. 7), are formed in the work 47 and over the stitch-finger and these stitches are fed forward by the feed-dog until they ride off of the tapered tongue of the stitch-finger thereby forming a raised ornamental seam 40 on the material being stitched.

It will be obvious that the stitch-finger may be removed by loosening the screw 40 and a stitch-finger of a different width placed on the presser-foot in order that seams of different widths may be produced. It is to be understood that the screw 31 may be adjusted in the slot 28 to vary the lateral throw of the presser-foot in accordance with the width of the stitch-finger.

45 50 Having thus set forth the nature of the invention, what I claim herein is:—

1. A presser-foot for sewing machines comprising a shank, a sole-plate carried thereby, and a stitch-finger carried by said sole-plate, said stitch-finger having an abruptly downwardly inclined 55 thread-deflecting portion.

2. A presser-foot for sewing machines comprising a shank, a sole-plate formed with a needle-opening and carried by said shank, and a 60 stitch-finger secured to the upper face of said

sole-plate, said stitch-finger having an abruptly downwardly inclined thread-deflecting portion extending through said needle-opening and a horizontally disposed rearwardly extending tongue.

3. A presser-foot for sewing machines comprising a shank, a sole-portion carried by said shank, said sole-portion being formed with a needle-opening, an unobstructed groove extending from the toe of said sole-portion to said needle-opening and a second groove extending from said needle-opening to the heel of said sole-portion, a stitch-finger carried by said sole-portion and extending into said needle-opening and through said second mentioned groove and means for adjustably and detachably securing said stitch-finger to said sole-portion.

4. A presser-foot for sewing machines comprising a shank, a sole-portion carried by said shank and formed with a needle-opening, a groove extending from the toe of said sole-portion to said needle-opening, and a clearance notch in rear of said needle-opening, and a stitch-finger adjustably secured to said sole-portion and having a downwardly inclined portion located in said needle-opening and a rearwardly extending tongue entering the clearance notch in rear of said needle-opening.

5. In combination with a sewing machine having a needle-bar adapted to be reciprocated in a fixed path, a thread-carrying needle secured to said needle-bar, a presser-foot, a stitch-finger carried by said presser-foot and formed with a downwardly inclined and rearwardly extending thread-deflecting portion, and means actuated by 35 said needle-bar for vibrating said presser-foot laterally relative to the needle, whereby the needle descends on first one side and then the other side of said stitch-finger and the needle-thread is laid across said stitch-finger.

6. In combination with a reciprocating needle and work-feeding mechanism, a laterally vibratory presser-foot, and a stitch-finger carried by said presser-foot and formed alongside the path of the needle with a downwardly inclined thread-deflecting portion.

7. In combination with a reciprocating needle and work-feeding mechanism, a stitch-finger having an abruptly downwardly inclined portion located adjacent said needle and means for laterally vibrating said stitch-finger and needle relative to each other.

8. In combination with a reciprocating needle and work-feeding mechanism, a stitch-finger having horizontally disposed portions located at different elevations and connected by an abruptly downwardly inclined portion located adjacent said needle and means for laterally vibrating said stitch-finger and needle relative to each other.

JOHN D. KARLE. 60
